United States Patent Office.

GEORGE LANE, OF NEW YORK, N. Y.

Letters Patent No. 99,918, dated February 15, 1870.

IMPROVEMENT IN NECK-TIES.

The Schedule referred to in these Letters Patent and making part of the same.

To all whom it may concern:

Be it known that I, GEORGE LANE, of the city, county, and State of New York, have invented a new and useful Improvement in Neck-Ties, the same constituting a new article of manufacture; and I do hereby declare that the following is a full, clear, and exact description of the same, reference being had to the accompanying drawing forming part of this specification, and which represents a view in perspective of a necktie made in accordance with my improvement.

My invention consists in a neck-tie made from any suitable material in two lengths or sections, each of which is equal to the half of the full length of the tie, or thereabouts, and both ends of each section similarly pointed or finished, after which the one end of one of the sections is made to overlap the one end of the other section and tacked or temporarily held thereto by stitches or otherwise, so that on the other or front ends of the tie formed by the united sections becoming worn or defaced, the stitching uniting said sections may be picked or cut and the ends of the sections reversed; that is, the ends of the sections previously tacked together brought in front, while the original front ends of the tie are tacked together.

In this way the back of the tie, which is comparatively protected when the article is in use, may be readily made to take the place of the front portion when worn or effaced, and that not unfrequently occurs while the rest of the tie is in good order or condition, owing to the usual frequent tying and untying and exposure of the tie at its ends or in front. By

making the tie, however, with four ends, as described, that is each section with two finished ends, and tacking the sections together as specified, a reversible character is secured to the tie as regards the substitution of its rear for its front portion without any cutting or fitting of new ends, and such change or reversal made in a few moments by other than an expert or seamstress.

A neck-tie with reversible ends, as described, constitutes a new article of manufacture, and will prove very economical, and the same may be put upon the market at but little or no greater cost than neck-ties as ordinarily made having two ends only.

In the accompanying drawing, which represents my improved neck-tie—

A and B represent the two sections, each formed with two finished ends, *a* *b*, that may be reversed and tacked together as represented and herein before described.

Another advantage may be found in the adjustability of such neck-tie as to length, by increasing or decreasing the lap of the joined ends.

What is here claimed, and desired to be secured by Letters Patent, is—

A neck-tie formed in sections, the ends of which are finished so as to be reversible as front or exposed ends, substantially as shown and described.

GEO. LANE.
